UNITED STATES PATENT OFFICE.

JOHAN PETTER SWENSON, OF CHICAGO, ILLINOIS.

DESIGN FOR A SPOOL-HOLDER.

SPECIFICATION forming part of Design No. 34,873, dated July 30, 1901.

Application filed March 30, 1901. Serial No. 53,736. Term of patent 7 years.

To all whom it may concern:

Be it known that I, JOHAN PETTER SWENSON, a citizen of the United States, residing at Chicago, in the county of Cook and State 5 of Illinois, have invented and produced a new and useful Design for a Spool-Holder, of which the following is a specification, reference being had to the accompanying drawings, in which—

10 Figure 1 is a perspective view of a spool-holder constructed in accordance with my design; Fig. 2, a vertical sectional view, and Fig. 3 a top plan view.

The essential feature of my design resides 15 in the peculiar shape of the article, as hereinafter fully described.

Referring to the drawings, A indicates a holder circular in shape and having a circular recess A'. Points B extend upwardly 20 from the bottom of the recess A', and a cir-

cular opening C is produced centrally in said bottom. The sides of the holder are made bulging, as shown at D, and contracted or grooved, as shown at E, adjacent to the upper end, and upon the bottom is produced a 25 circular boss F, which surrounds the central aperture C.

The walls of the recess A' are substantially straight and slightly inclined, but at their outer edges are rounded slightly, as shown 30 at G.

Having thus fully described my invention, what I claim as new, and desire to secure by Letters Patent of the United States, is—

The design for a spool-holder, substantially 35 as herein shown and described.

JOHAN PETTER SWENSON.
